UNITED STATES PATENT OFFICE.

PHILIP S. MCLEAN, OF BLOOMFIELD, NEW JERSEY, ASSIGNOR, BY MESNE ASSIGNMENTS, TO BENJAMIN ELECTRIC MANUFACTURING COMPANY, OF CHICAGO, ILLINOIS, A CORPORATION OF ILLINOIS.

SWIVEL ATTACHMENT-PLUG.

1,398,077.

Specification of Letters Patent.

Patented Nov. 22, 1921.

Application filed April 25, 1917. Serial No. 164,519.

To all whom it may concern:

Be it known that I, PHILIP S. MCLEAN, resident of Bloomfield, in the county of Essex and State of New Jersey, have invented 5 a new and useful Improvement in Swivel Attachment-Plugs, of which the following is a specification.

The invention relates to attachment plugs.

It relates particularly to swivel attachment plugs in which a screw shell is arranged to rotate independently of the main body of the plug so that the plug may be inserted in a lamp socket without twisting the wires to which the plug is attached.

One of the objects of the invention is to provide an improved swivel attachment plug made of a minimum number of simple parts and one which is particularly easy to assemble.

A further object is to provide an improved attachment plug, the base portion of which may be easily attached to conductor wires of equal length and which when so attached relieves the strain from the point of attachment of the cords and one in which the remaining portions of the plug may be easily assembled without requiring that they be threaded over the conductor cords and without requiring the adjustment of any screws, nuts, bolts or the like.

Other objects and advantages of the invention will appear from the following specification.

An embodiment of the invention is shown 25 in the accompanying drawings. The views of the drawings are as follows:

Figure 1 is a separated view of the plug, showing the relation of the parts in assemblage;

Fig. 2 is a cross section of the plug assembled;

Fig. 3 is a cross section of the assembled plug at right angles to Fig. 2; and

Fig. 4 is a top view of the assembled plug.

The plug comprises in general an insulating base 1, carrying electrical terminals 2 and 3, a screw shell 4 arranged to be mounted to rotate about the terminals, an insulating spacer 5 for insertion within the screw shell to insulate the terminals from each other and the shell, and a center contact 6 including a yielding spring 7 carried by the spacer and adapted to engage one of the terminals to hold the parts together and form a center contact.

The insulating base 1 is formed of any suitable insulating material, such as fiber composition, hard rubber, porcelain or the like, preferably a material which may be easily molded. The exterior of the base is 55 shaped to any desired configuration to enable it to be readily grasped by the fingers of an operator. The top surface has a circular projection 8 which acts as a guide for the rotatable screw shell as will be explained in 60 more detail hereinafter. Extending axially through the base is an opening 9 of sufficient size to readily accommodate insulated conductor cords, such as are usually attached to a plug of this character.

The electrical terminals 2 and 3 are preferably embedded in the base at the time it is made and for convenience in manufacturing their inside surfaces are in line with the periphery of the opening 9. Each terminal 75 has an offset portion 10 forming a shoulder for the purpose of insuring that the terminals will be held rigidly in the base. It is to be understood that these terminals may be attached to and carried by the base in any 80 other suitable manner.

The terminal 2 has a lateral projection 11 which electrically engages the screw shell as will be later described. Both terminals are of approximately equal length so that 85 their ends extend equal distances from the surface of the base and they are provided with openings 12 and 13 respectively, the bottom surfaces of which are equal distances from the base. Each terminal also carries 90 binder screws 14, the heads of which are on the outer faces of the terminals.

By means of this construction, the conductor cords may be quickly and easily attached to the base, as illustrated in Fig. 1. 95 Wires may be cut off in equal lengths, stripped of insulation for equal distances from their ends, passed through the opening 9 in the base and through the openings 12 and 13 in the terminals and attached to the outer 100 faces of the terminals by means of the binder screws. Any withdrawal strains on the cord are taken up by the bottom edges of the openings 12 and 13 in the terminals, the cords having a double right angle bend in 105 passing from the point of attachment over

these bottom edges and out through the axial opening. The base may thus be very easily and quickly wired after which the remaining portions of the plug may be 5 snapped into position.

The rotatable screw shell 4 is of the usual type and forms the outer contact of the plug engaging the screw shell of the lamp socket in which the plug is inserted. The shell is 10 flanged about an insulating washer 15 so as to form an inwardly extending annular rib 16 and a shoulder 17. The annular rib 16 fits around the circular projection 8 on the base so that the shell may be readily rotated 15 and guided to prevent it from being displaced laterally. The shoulder 17 engages the projection 11 on the terminal 2 and thereby completes an electrical connection with the terminal which permits the shell 20 to be rotated. An insulating ring 18 surrounds the shell and abuts the ring 15 to prevent any of the conducting parts projecting beyond the lamp socket when the plug is in circuit. This shell may be readily 25 put in place over the terminals as will be clear by referring to Fig. 1, by simply tilting it to a slight angle to permit the rib 16 to be inserted under the projection 11 of the terminal 2, the distance between the 30 terminal 3 and the opposite side of the rib being such as to readily permit the shell to be laterally displaced a distance sufficient to properly and easily position the shell. The shoulder 8, in addition to acting as a bearing shoulder for the screw shell, prevents 35 the insertion of a wire or other instrument into the interior of the plug between the shell and base.

The insulating spacer or filler 5 is formed 40 of suitable insulating material, such as fiber composition, hard rubber, porcelain and the like, and is shaped to fit within the screw shell to insulate the terminals from the shell and from each other. The outer end 45 or tip of the spacer is preferably rounded to facilitate the insertion of a plug in a socket. The end of the filler which is inserted in the screw shell is provided with two recesses 19 and 20 of suitable size and 50 shape to receive the terminals 2 and 3 with the conductor cords attached thereto. The outer walls 21 and 22 of the recesses insulate the terminals from the screw shell and the dividing wall 23 extending between the recesses insulates the terminals from each other.

The recesses 19 and 20 communicate with 60 sockets 24 and 25 in which the ends of the terminals 2 and 3 seat so that when the spacer is placed in position the bottoms of these sockets contact with the tops of the terminals and prevent the spacer being forced down to tightly grip the shoulder 17 on the screw shell and prevent its turning. 65 The length of the spacer is such that when

the terminals engage the bottoms of the sockets 24 and 25, the bottom surfaces of the spacer contact the shoulder 17 with sufficient clearance to enable the shell to be readily rotated and at the same time to be 70 held in position. The side wall 21 has a slot 26 therethrough to accommodate the lateral projection 11 on terminal 2.

The center contact 6 comprises a suitable screw engaging a nut 27, preferably embedded in the spacer 5. The spring 7 is held beneath the head of the center contact screw 6 and projects through an opening 28 in the spacer, the lower or free end of the spring being provided with a shoulder 29 which, 80 when the plug is assembled, lies beneath the top edge of the opening 13 in the terminal 3 and electrically connects the center contact with this terminal and at the same time holds the parts together. This construction 85 permits the insulating spacer to be readily inserted into the screw shell and automatically locked into position without the insertion of any screws or the tightening of any nuts or bolts. If it is desired to remove 90 the spacer and disassemble the plug a small instrument may be inserted in the opening 28 to release the shoulder 29 from the terminal 3.

An exceedingly simple, inexpensive and 95 efficient swivel attachment plug is accordingly provided, the base of which may be easily attached to conductor cords of equal length and the remaining parts of the plug subsequently assembled on the base by 100 simply inserting them in position and without manipulating any screws, nuts or bolts. The plug may be equally as easily taken apart by simply pushing the spring 7 over and removing the spacer and the screw shell, 105 after which the terminals are readily accessible.

It is to be understood that the structure shown is for purposes of illustration only and that various changes may be made 110 therein without departing from the spirit and scope of the appended claims.

What I claim is:

1. A swivel attachment plug comprising 115 an insulating base having an opening therethrough for the passage of conductor cords, electrical terminals carried by said base and projecting substantially equal distances therefrom, a screw shell mounted to rotate about said terminals in electrical engagement with one of them, an insulating spacer adapted to be inserted within the shell to rotatably hold the same in place and engaging the ends of the terminals to prevent the spacer binding the shell against rotation, and means carried 120 by the spacer electrically connected to the other terminal for holding the parts together and forming a center contact.

2. An attachment plug having an insulating 125 base provided with an opening for the 130

passage of conductor cords, electrical terminals carried by said base and projecting substantially equal distances therefrom, said terminals having openings therein the bottom edges of which are substantially equal distances from the base whereby cords of equal length may be passed through the openings and attached to the outer surface of the terminals to relieve the strain from the point of attachment, a screw shell mounted to rotate about the terminals in electrical engagement with one of them, an insulating spacer adapted to be positioned within the shell to rotatably hold it in position and insulate the terminals, and yielding contact means carried by the spacer arranged to engage under the upper edge of the opening in the other terminal to hold the parts together and form a center contact.

3. A swivel attachment plug comprising an insulating base having an opening therethrough for the passage of conductor cords, electrical terminals projecting from said base, a screw shell having an annular rib forming a shoulder within the shell, said shell being mounted about the terminals so that the rib thereon rotates about a shoulder on the base, one of the terminals being provided with a portion arranged to electrically engage the shoulder on the shell, an insulating spacer adapted to be positioned within the shell to insulate the terminals from each other and from the shell, said spacer having surfaces engaging the ends of the terminals and a bottom surface engaging the shoulder on the shell to rotatably hold the shell in position, and means carried by the spacer for releasably engaging the other terminal to hold the parts together and form a center contact.

4. A swivel attachment plug comprising an insulating base having an axial opening for the passage of conductor cords, integral electrical terminals carried by said base and projecting substantially equal distances therefrom on opposite sides of said openings and in line with the periphery thereof, said terminals having openings therein the bottom edges of which are substantially equal distances from the base and one of said terminals having a projection struck up therefrom, a screw shell having a shoulder thereon, said shell being mounted so as to rotate about said terminals with the shoulder in engagement with the projection on the one terminal, an insulating spacer adapted to be positioned within the shell to insulate the terminals from the shell and from each other, said spacer having surfaces engaging the tops of the terminals and bottom surfaces engaging the shoulder on the shell to rotatably hold the shell in position, and means including a yielding spring contact engaging beneath the upper surface of the opening in the other terminal for holding the

spacer in position and the parts together and forming a center contact.

5. A swivel attachment plug comprising an insulating base having a circular projection on one surface thereof, integral electrical terminals embedded in said base and projecting substantially equal distances therefrom, one of said terminals having an integral lateral projection and both of said terminals having openings therethrough the bottom edges of which are substantially equal distances from the base whereby wires may be passed through the openings and attached to the outer surfaces of the terminals, a screw shell having an annular rib on the inside thereof, said shell being mounted so that the rib rotates about the circular projection on the base with the shoulder in electrical engagement with the lateral projection on one of the terminals, an insulating spacer adapted to be positioned within the shell to insulate the terminals from the shell and from each other, said spacer having surfaces engaging the tops of the terminals and other surfaces engaging the shoulder on the shell whereby the shell is rotatably held in position, and means including a spring contact adapted to engage beneath the top edge of the opening in the other terminal to hold the parts together and form a center contact.

6. A swivel attachment plug comprising a base having a cord passage and provided with a bearing shoulder, a screw shell swiveled on said bearing shoulder and provided with an inwardly projecting contact shoulder, a projecting terminal post on the base within the screw shell provided with an outwardly projecting contact overstanding the inwardly projecting shoulder on the screw shell, an insulating spacing member separable from the base and holding the screw shell in swiveling engagement on the bearing shoulder, means for detachably securing said insulating spacing member to the base, a second terminal on the base and an end contact electrically connected with said second terminal.

7. A swivel attachment plug comprising a base having a cord passage and a circular bearing shoulder surrounding the cord passage, a screw shell swiveled on said bearing shoulder and provided with an inwardly projecting contact shoulder, a projecting terminal post on the base within the screw shell provided with an outwardly projecting contact overstanding the inwardly projecting shoulder on the screw shell, a separately formed insulating spacing member separably secured to the base and when thus secured to the base holding the screw shell in swiveling engagement on the bearing shoulder whereby said circular bearing shoulder covers the joint between the base and the screw shell, a second terminal on

the base and an end contact electrically connected with said second terminal.

8. An attachment plug comprising an insulating base having a cord passage and provided with a bearing shoulder, an outstanding contact on the base projecting outwardly beyond said bearing shoulder, a screw shell having an inwardly projecting contact shoulder engageable beneath the outstanding contact by movement of the shell in tilted relation over said contact and lateral shifting of the shell to carry said contact shoulder beneath the outstanding contact, said shell having a bearing portion engageable over the bearing shoulder on the base upon the straightening of the shell on the base, whereby said bearing shoulder holds the screw shell swiveled on the base with its contact flange engaged beneath the outstanding contact on the base, an insulating spacer detachably secured to the base and holding the screw shell against such tilting on the base as would free it from the bearing shoulder, an end contact and terminals on the base within the screw shell electrically connected with the end contact and the outstanding contact aforesaid.

9. An attachment plug comprising an insulating base having a cord passage and provided with a bearing shoulder, an outstanding contact on the base projecting outwardly beyond said bearing shoulder, a screw shell having an inwardly projecting contact shoulder engageable beneath the outstanding contact by movement of the shell in tilted relation over said contact and lateral shifting of the shell to carry said contact shoulder beneath the outstanding contact, said shell having a bearing portion engageable over the bearing shoulder on the base by the straightening of the shell on the base, whereby said bearing shoulder holds the screw shell swiveled on the base with its contact flange engaged beneath the contact on the base, an insulating spacer engaging the screw shell and holding it against such tilting movement on the base as would free it from the bearing shoulder, means for detachably securing said insulating spacer to the base, a spring catch yieldingly securing said spacing member to the base, an end contact, and terminals on the base within the screw shell electrically connected with the end contact and the outstanding contact aforesaid.

10. An attachment plug comprising a base, a sliding contact member on the base, a screw shell in sliding engagement with said contact, a spacing and guiding member engaging said screw shell and holding the same in sliding engagement with the contact member, a yielding spring catch detachably securing said positioning and guiding member to the base, an end contact and terminals on the base electrically connected

with said end contact and the sliding contact.

11. An attachment plug comprising a base having a cord passage and provided with a bearing shoulder, an outstanding contact on the base projecting outwardly beyond said bearing shoulder, a screw shell having an inwardly projecting contact shoulder engageable beneath the outstanding contact by the movement of the shell in tilted relation over said contact and the lateral shifting of the shell to carry said contact shoulder beneath the outstanding contact, said shell having a bearing portion engageable over the bearing shoulder on the base by the straightening of the shell on the base, whereby said bearing shoulder holds the screw shell swiveled on the base with its contact flange engaged beneath the outstanding contact on the base, a spacer detachably secured to the base and having a sliding fit within the end of the screw shell to thereby hold the screw shell against such tilting movement on the base as would free it from the bearing shoulder, an end contact and terminals on the base within the screw shell electrically connected with the end contact and the outstanding contact aforesaid.

12. An attachment plug comprising an insulating base having a cord passage and provided with a bearing shoulder, a screw shell swiveled at the base on said bearing shoulder and provided at said base portion with an inwardly projecting contact shoulder, a contact on the insulating base engaging over said contact shoulder, an insulating spacing member detachably secured to the insulating base having an abutment shoulder overstanding the contact shoulder on the screw shell, an end contact and terminals on the insulating base within the screw shell electrically connected with the end contact and the contact on the insulating base.

13. An attachment plug comprising a base having a cord passage, projecting terminals on said base provided with openings therein affording strain reliefs for wires passed therethrough, a swiveled screw shell on the base, a spacing member engaged on the projecting terminals, an end contact on said spacing member, a spring catch electrically connected with said end contact and provided with a shoulder adapted to snap into the opening in one of the terminals and sliding connections between the other terminal and the screw shell.

14. A swivel attachment plug having an insulating base provided with an opening therethrough for the passage of conductor cords, electrical terminals carried by said base and projecting therefrom, an insulating spacer, a screw shell rotatably mounted between the base and spacer and arranged to electrically engage one of the terminals, means carried by the spacer for releasably

engaging the other terminal to hold the parts together and form a center contact, and positive means for preventing withdrawal of the insulating base from the screw shell, 5 when the spacer is in position with respect to the screw shell.

15. A swivel contact attachment plug comprising an insulating base, a center contact supported thereby, a threaded shell contact swiveled with respect thereto, means for preventing said threaded shell contact from slipping off said insulating base, comprising an insulating hand-hold member, wiring terminals supported by said insulating hand- 15 hold member and electrically connected with said shell and center contacts respectively, and a quick-detachable spring connection between said insulating base and hand-hold member, whereby said hand-hold member 20 can be quickly detached with respect to said insulating base to permit said threaded shell contact to be removed from said insulating base.

16. A swivel contact attachment plug comprising an insulating base, a center contact supported thereby, a shell contact swiveled with respect thereto, an insulating hand-hold member, wiring terminals supported thereby within said swivel shell contact, and electrically connected with said shell and center contacts respectively, said insulating base being recessed to receive said wiring terminals, and a quick-detachable spring connection between said insulating base and hand- 35 hold member.

17. A swivel contact attachment plug comprising an insulating base, a center contact supported thereby, a threaded shell contact swiveled with respect thereto, an insulating hand-hold member, two wiring terminals supported thereby, electrically connected to said center and shell contacts respectively, said insulating base being recessed to receive the wiring terminals, one of said wiring ter- 40

minals comprising a binding screw and being provided with an edge over which the conductor leading to said binding screw is bent and a quick-detachable spring connection between said insulating base and said hand-hold member. 45

18. An attachment plug having an insulating base provided with an opening for the passage of conducting wires, an annular projecting rib, electrical terminals carried by said base and projecting therefrom, a screw shell mounted to rotate about the terminals in electrical engagement with one of them and to be guided by the annular rib on the base, an insulating spacer arranged to be positioned within the screw shell to insulate the terminals and hold the screw shell in place, and means carried by the spacer electrically connected to the other terminal for holding the parts together and forming a center contact. 50

19. A swivel attachment plug having an insulating base provided with an opening for the passage of conductor wires and with an annular projecting rib, electrical terminals carried by said base and projecting therefrom, said terminals being arranged to form strain relief means for relieving the strain at the point of attachment of the conductor cords, a screw shell mounted to rotate about the terminals in electrical engagement with one of them and guided by the annular rib on the base, an insulating spacer adapted to be positioned within the screw shell to insulate the terminals and rotatably hold the screw shell in position, and means passing through an opening in the spacer and connected to the other terminal to hold the parts together and form a center contact. 70

In testimony whereof, I have hereunto set my hand. 75

PHILIP S. McLEAN.
